UNITED STATES PATENT OFFICE.

PURMORT BRADFORD, OF NEW HAVEN, CONNECTICUT, ASSIGNOR TO SARGENT & CO., OF SAME PLACE.

DESIGN FOR FASTENER FOR MEETING-RAILS OF SASHES.

Specification forming part of Design No. 5,288, dated September 26, 1871.

To all whom it may concern:

Be it known that I, PURMORT BRADFORD, of New Haven, in the county of New Haven and State of Connecticut, have invented a new and original Design for Sash-Fastener; and I do hereby declare the following, when taken in connection with the accompanying drawing and the letters of reference marked thereon, to be a full, clear, and exact description, and which said drawing constitutes part of this specification and represents a rear view of a fastener.

This invention relates to a design for the rear or back side of sash-fasteners, the object being the ornamentation of that part of the fastener which is exposed to passers on the outside the window, as in basement windows, this part having heretofore been without ornamentation; and the invention consists in sinking the rear face of

the fastener to form a panel, in which any tracery or ornament may be formed. B is the case, within which the lever is pivoted. This surface I sink in molding for the casting, or raise the edge, so as to form a panel; and on the surface, by the same process, I form any desirable ornamentation, which rises flush with the edge, and with the edge is polished, and the bed of the panel "matted" or otherwise finished.

I claim—

The design for sash-fastener described, consisting of an ornamented panel on the back or rear of the fastener.

PURMORT BRADFORD.
